Jean E. Vivaudou and Henry G. Lubin,
New York, N. Y.

Application March 1, 1940, Serial No. 90,606

Term of patent 3½ years

To all whom it may concern:

Be it known that we, Jean E. Vivaudou and Henry G. Lubin, subject of Great Britain and citizen of the United States, respectively, and both residents of New York city, in the county of New York and State of New York, have invented a new, original, and ornamental Design for a Combined Perfume Box, Sachets, and Container Therefor, of which the following is a specification, reference being had to the accompanying drawing, forming a part thereof.

Fig. 1 is a front elevational view of a combined perfume box, sachets, and container therefor, showing our new design,

Fig. 2 is a side elevational view of the same.

We claim:

The ornamental design for a combined perfume box, sachets, and container therefor, as shown.

JEAN E. VIVAUDOU.
HENRY G. LUBIN.
